Primary Examiner — Daniel Bui*Assistant Examiner* — Khawaja Anwar(74) *Attorney, Agent, or Firm* — Faegre Baker Daniels LLP(57) **CLAIM**

The ornamental design for a whiskey bullet, as shown and described.

DESCRIPTION

FIG. 1 is a front perspective view of a whiskey bullet, showing our new design;

FIG. 2 is a first side elevation view thereof;

FIG. 3 is a second side elevation view thereof;

FIG. 4 is a front elevation view thereof;

FIG. 5 is a back elevation view thereof; and,

FIG. 6 is a top plan view thereof.

The broken line in the figure drawings represents unclaimed environment only and forms no part of the claimed design.
